UNITED STATES PATENT OFFICE.

ANDREW A. KRAMER, OF KANSAS CITY, AND CHARLES E. CHAPMAN, OF INDEPENDENCE, MISSOURI; SAID CHAPMAN ASSIGNOR TO SAID KRAMER.

CONDENSER.

Application filed April 26, 1922. Serial No. 556,564.

To all whom it may concern:

Be it known that we, ANDREW A. KRAMER and CHARLES E. CHAPMAN, citizens of the United States, residing at Kansas City and 5 Independence, respectively, in the county of Jackson and State of Missouri, have invented certain new and useful Improvements in Condensers; and we do declare the following to be a full, clear, and exact description of 10 the invention, such as will enable others skilled in the art to which it appertains to make and use the same, reference being had to the accompanying drawings, and to the figures of reference marked thereon, which 15 form a part of this specification.

This invention relates to surface condensers in which a casing or chamber is provided for the admission of steam, there being 20 means incorporated for passing cooling fluid over the walls of the casing or chamber so that the steam or vapor will be condensed into liquid.

The invention is particularly adapted for 25 use as a part of an apparatus for distilling water and means is provided whereby the distilled liquid can be reconverted into vapor or steam to be recondensed.

The primary object of the invention is to 30 provide an inexpensive, efficient form of surface condenser and one which may be readily repaired.

The particularly novel features of the invention will be referred to hereinafter, reference being had to the accompanying drawings, in which—

Fig. 1 is a perspective view of a condenser constructed in accordance with our invention, parts being broken away to show the interior construction thereof.

Fig. 2 is a vertical, cross sectional view 40 through the complete condenser.

Fig. 3 is an enlarged sectional view of one of the horizontal partition supports.

Fig. 4 is a like view of a different form of 45 support.

Fig. 5 is a fragmentary, sectional view of the discharge end of the condensate-receiving portion of the condenser, and

Fig. 6 is a fragmentary, sectional view 50 through a slightly modified form of condensate chamber and condensing water-receiving trough.

The condenser is shown as consisting of two triangular end plates 1 and 2, which extend substantially the height of the con-

denser with their apexes at the top. The end plates are preferably flanged at the base portions, as indicated at 3 and 4, to add strength and to provide base portions by means of which the condenser may be supported.

The condenser is shown as substantially triangular in cross section and between the end plates 1 and 2 is a curved plate 5, which is bent in the center in substantially the form of a U, the end edges of the plate 5 being flanged, as at 6 and 7 and the flanges being fastened to the inner faces of the end plates 1 and 2 by bolts 8 and 9 respectively.

The side walls 10 and 11 of the bent plate 5 converge to conform to the angles of the 70 edges of the plates 1 and 2 and their ends are in-bent to form supporting flanges 12 and 13.

Above the edges of the plate 5 are two converging plates 14 and 15, which extend to 75 the top of the condenser, where their upper ends meet, as at 16, so that they can be welded together. The upper and lower plates are welded together as at 12' in any well known manner so that a tight joint will 80 be made at their meeting edges. The plates 14 and 15 are provided with flanges 17 and 18, which are also bolted to the end plates 1 and 2 by the bolts 8 and 9. The bottom 85 ends or edges of the plates 14 and 15 are turned in and rest upon the flanges 12 and 13. Each bottom end consists of a laterally disposed portion 19, bent back upon itself in the form of a hook to provide a parallel portion 20, as best seen in Fig. 3, the portion 20 being spaced from the portion 19 to provide a groove to receive the hooked over or inturned longitudinal edge 21 of a baffle or partition 22, which is the intermediate baffle or partition in the condensing chamber 23 90 enclosed by the bent plate 5 and the two complementary aligning plates 14 and 15. The intermediate partition terminates short of the end plate 1 and it is provided with a depending flange 24 so that it can be grasped 95 when the plate 1 is removed, and slid on its support 19 to remove it in the event that access to the interior of the condenser is desired.

A similar plate 22' is provided for the 105 lower baffle or partition and it engages in a groove between the lateral flange 19' and the bent-over flange 20' on a bracket plate 25, welded to the inside of each plate 14 and 15. The lower baffle or partition plate 110

terminates short of the end plate 2 but it may be withdrawn through the opening closed by the end plate 1 if the end plate 1 is removed.

5 There is a top baffle plate corresponding to the baffle plate 22', the top baffle plate being designated 26, and it consists of a flat strip guided between the pairs 27 and 28 of angle guides.

10 The end plate 1 is provided with an inlet orifice or port 29, by means of which steam or vapor may enter the condensate chamber 30. It may pass the length of the condenser, past the short end of the baffle 22', returning the length of the condenser, then over the short end of the baffle 22 for the full length of the condenser, and then over the baffle 26, where practically all of the condensable contents of the vapor will be condensed, the non-condensable gases passing out through the discharge orifice 27. The condensed vapor will gravitate to the condensate chamber 30.

15 The condensation takes place because the entire side walls of the condenser are subjected to cooling water which may be introduced into the trough 28, running the entire length of the condenser and having the inclined deflectors 29 and 30 to direct 20 the flow to the bottom of the trough or hopper, the edges of which are formed with serrations 31 so that slight orifices are provided, through which the water may stream over the outside surfaces of the walls of 25 the condenser and thereby maintain the walls cool enough to cause condensation of the vapor entering through the port or orifice 29.

20 The cooling water will be caught in longitudinal troughs 32 and 33, having openings 34 and 35 by means of which the water may be led to a sump to be re-delivered to the trough 28 or whereby the water may pass off to a drain, if desired.

45 The bottom of the chamber 23 and particularly the bottom of the condensate chamber or portion 30 which really is a subjacent chamber divided from the condensing chamber 23 by the partition 22', has a discharge 50 port 36, normally closed but which may be opened if desired to draw off the contents of the chamber 30. The chamber 30 also discharges into a gooseneck or pipe 37, which can be turned about the axis of the 55 coupling 38 to cause it to become effective as a drain at any predetermined level in the chamber 30. For example, if the gooseneck is in a vertical position, the level of the liquid in the chamber 30 will be higher than 60 if it is in a horizontal position.

In order to allow the level of the liquid to rise above the inlet opening 29, the pipe leading to the inlet opening 29 should be vertical or substantially so for a portion of 65 its length. Then if the steam passes

through the orifice 29, it may bubble through the liquid 39 in the chamber 30 and if the steam is hot enough, it may reconvert the condensed liquid into vapor or at least part of the liquid into vapor so that it may be 70 recondensed, thereby in effect causing a re-distillation, making the water purer although it is not necessary to re-distill it because if the gooseneck is twisted or turned on the connection 38 so that the level of the liquid 39 will be below the top of the orifice 29, the steam may enter the condenser by passing over the liquid to pass through the tortuous passages formed by the baffles so that a single condensation will take place. 75

In Fig. 6 we have shown a slightly modified form of condenser base in which the plate 5 corresponding to the plate 5 is bent intermediate its ends and flared outwardly to form a trough 33'. In the preferred 80 form, the troughs are welded to the sides of the plate 5, whereas in the modification shown in Fig. 6, the troughs are formed integral with the plates, and supplemental plates corresponding to plates 14 and 15 are 85 welded at 40.

85 By reference to the drawings it will be observed that the troughs are arranged above the bottom of the condenser and it is intended that these troughs will ordinarily be above the normal level of the condensate within the chamber 33. The purpose of this is to allow the condensate 39 to be reconverted into vapor by the incoming steam. If the cooling water surrounded the lower portion of the casing or the condensate chamber 30, the temperature would be reduced 90 too much to permit a reconversion into vapor but in actual practice the condensate may remain at a temperature somewhere around 200° F., or a little above that so that the steam may carry along with it a considerable portion of the previously condensed steam to be reconverted into liquid, thereby 95 permitting the same liquid to be re-distilled 100 as many times as desired. 110

If it is desired to have access to the interior of the condenser, the end plate 1 may be removed and the baffles slid longitudinally so that they can be taken out, then the operator may readily enter the condenser 115 for inspection or repairs.

120 Of course, it is to be understood that a supply pipe or pipes may be provided over the top of the trough or hopper-shaped receiver for the liquid so that the liquid may be uniformly distributed over the surfaces of the side members of the condenser to provide a uniform temperature throughout.

125 What we claim and desire to secure by Letters Patent is:

1. A surface condenser comprising end plates, a plate bent to form a bottom and side walls and having its edges attached to said end plates to cooperate therewith in 130

forming a lower collecting chamber and an upper flow chamber, the upper edges of the side walls being turned inwardly to form shelves, supplemental side plates, having 5 their lower edges turned inwardly and resting on said shelves and having their edges secured to said end plates, means for delivering fluid to the collecting chamber, means for delivering fluid from the collecting 10 chamber, and means for delivering fluid over the outer faces of said side walls in thin streams.

2. A surface condenser comprising end plates, a plate bent to form a bottom and 15 side walls and having its edges attached to said end plates to cooperate therewith in forming a lower collecting chamber and an upper flow chamber, the upper edges of the side walls being turned inwardly to form 20 shelves, supplemental side plates, having their lower edges turned inwardly and resting on said shelves and having their edges secured to said end plates, means for delivering fluid to the collecting chamber, means 25 for delivering fluid from the collecting chamber, and means for delivering fluid over the outer faces of said side walls in thin streams, the inturned edges of the sup-

plemental side plates having backturned, spaced members, forming horizontal grooves 30 and a baffle slidably supported on said backturned members and having backturned edge members, slidable in said grooves.

3. A surface condenser comprising end plates, a plate bent to form a bottom and side walls and having its edges attached to 35 said end plates to cooperate therewith in forming a lower collecting chamber and an upper flow chamber, the upper edges of the side walls being turned inwardly to form 40 shelves, supplemental side plates, having their lower edges turned inwardly and resting on said shelves and having their edges secured to said end plates, means for delivering fluid to the collecting chamber, 45 means for delivering fluid from the collecting chamber, and means for delivering fluid over the outer faces of said side walls in thin streams, the supplemental side plates being welded to the main side plates at their 50 line of junction.

In testimony whereof we affix our signatures.

ANDREW A. KRAMER.
CHARLES E. CHAPMAN.
